VIBRATING MECHANISM

Alexander J. Roubal, Milwaukee, Wis., assignor to Allis-Chalmers Manufacturing Company, Milwaukee, Wis.

Application April 12, 1957, Serial No. 652,411

4 Claims. (Cl. 209—367)

This invention relates to a vibrating screen assembly. In particular this invention relates to a screen assembly of the type having a screen box with one or more bottom screening surfaces with the screen box being mounted for vibratory movement and having vibrating mechanisms attached to the screen box for vibrating the box and its screening surfaces.

One type of vibrating mechanism often provided to impart the desired vibratory movement to a screen box is disclosed in C. S. Lincoln et al., U.S. Patent 2,144,382, January 17, 1939. This type of vibrating mechanism has one shaft connected to a motor for operating the mechanism and a second shaft within the unit geared to the first shaft to rotate in the opposite direction of the first shaft. Each shaft is provided with eccentric weights mounted thereon and as the weights are rotated about their respective shafts in opposite directions a vibratory movement along a straight line path is produced and transmitted to the screen box.

It has at times been necessary to provide a screen assembly with a pair of such vibrating mechanisms in order to produce sufficient vibratory motion to satisfy the requirements of particular installations. In such installations it was found desirable to utilize a sheave between the two mechanisms to drive the mechanisms from the center of the assembly rather than from a remote end of the operating shaft. Such a center drive was found desirable to reduce the tendency of material traveling over the screening surface to move to one side of the screen as often occurred when the operating shaft was driven by a sheave on a remote end of the shaft. An illustration of such an arrangement in which a sheave is mounted between two mechanisms is found in W. T. Shaler, U.S. Patent 2,097,347, October 26, 1937. Although the center drive arrangement as shown in this Shaler patent lessened the likelihood of material shifting over to one side of the screen this arrangement was not entirely satisfactory. For example, this arrangement was furnished with a rather complicated coupling arrangement between the two vibrating mechanisms. A disadvantage of that arrangement arises from the necessity of periodically replacing endless belts that transmit rotary power to a sheave on the operating shaft. An arrangement such as shown in this Shaler patent necessitated a considerable amount of dismantling of the assembly in order to get the endless belts around the operating shaft and the sheave.

An object of the present invention is to provide a vibrating screen with a pair of vibrating assemblies with each having a separate operating shaft both driven from approximately the center of the assembly with a removable timing connection between the two operating shafts to establish and maintain predetermined timing between the vibrations of the two vibrating mechanisms with the timing connection being removable so that endless driving belts may be easily removed and replaced without substantial dismantling of the assembly.

2

Another object of the present invention is to provide a new and improved timing connection between a pair of vibrating assemblies being of simple construction and having flexibility to provide smooth and even distribution of vibratory forces across the entire width of a screen box to insure an even distribution of material to be screened across the entire width of the screening box as the material advances through the screen box.

Another object of the present invention is to provide an improved and simplified timing connection between a pair of vibrating assemblies that will operate satisfactorily even when the rotational axis of one of the vibrating assemblies may not be perfectly connected with the axis of the other assembly.

According to a preferred embodiment of the present invention a pair of vibrating mechanisms is arranged with their operating shafts axially aligned and in a linear arrangement transverse of side walls of a screen box. Each of the operating shafts extend inwardly toward each other to approximately the center line of the screen box. A sheave is mounted on each of the adjacent ends of the two operating shafts. The adjacent ends of the operating shafts and the sheaves mounted thereon are spaced apart from each other a distance sufficient to permit endless driving belts to be slipped between the ends of the shafts and the two sheaves so that they can be fitted over both of the sheaves without dismantling substantial portions of the assembly. To provide the desired timing connection between the two vibrator operating shafts the two sheaves are apertured and a timing pin is provided for insertion therein to provide a connection between the two sheaves and their respective vibrator operating shafts. In order to provide flexibility to this connection to insure an even distribution of vibratory forces across the entire width of the screen box and thereby maintain an even distribution of material across the screen box a flexible bushing which may be made of rubber is fitted over at least a portion of the timing pin. The pin and the flexible sleeve are arranged to provide a resilient connection between the pin and at least one of the sheaves to provide the desired flexibility in this timing connection.

Other objects and advantages of this invention will become apparent as the description of the invention proceeds.

In the accompanying drawings which form a part of this specification, a preferred embodiment of the present invention is illustrated wherein:

Fig. 1 is a view in elevation of a screen assembly according to this invention;

Fig. 2 is a partial end view of the assembly shown in Fig. 1 with portions of certain structure shown in cross section; and

Fig. 3 is an enlarged view of a portion of a structure shown in cross section in Fig. 2.

The vibrating screen illustrated in the drawing comprises a screen box 10 having a pair of vertical longitudinal side walls 11 and 12. The side walls 11 and 12 are spaced apart and parallel to each other to support between them a screening surface or deck 13. The screen has a feed hopper 14 and a discharge end 15 and the fines pass through the screen 13 while the oversize passes over the screen to the discharge end in the manner well known to others skilled in this art. The screen is mounted for vibratory motion and this may be done as shown where the screen box 10 is suspended by cables 16 which are attached to an overhead support 17 which may be part of the building in which the screen is housed. The cables 16 are here shown attached to the overhead support 17 through springs 18 which may be either in tension or compression.

Mounted rigidly on the screen box 10 by means of supports 19 and 20 is a pair of vibrators 21 and 22 which may be operated by means of a motor 23 mounted on the overhead support 17 and which operates the vibrators through a plurality of endless belts 24 in a manner described in greater detail hereinafter. The supports 19 and 20 serve not only to support the weight of the vibrating mechanisms 21, 22 but also serve to transmit the vibrating force to the screen body 10 and the screening surface 13. The vibrating mechanisms 21, 22 may both be of the type described in C. S. Lincoln et al., U.S. Patent 2,144,382. The vibrating mechanisms 21, 22 are operated by the rotation of operating shafts 25, 26.

The vibrating mechanisms 21, 22 are mounted upon the support member 20 with operating shafts 25, 26 axially aligned in linear arrangement along the support 20 and accordingly are transverse to the side walls 11 and 12 of the screen box 10. The operating shafts 25, 26 extend inwardly toward each other to approximately the longitudinal center of the box 10. Adjacent ends 27, 28 of the shafts 25, 26 are spaced apart from each other a predetermined distance d^1 . A pair of sheaves 31, 32 are provided to receive rotary motion transmitted from the motor 23 by the endless belts 24 and in turn transmit this rotary motion to the operating shafts 25, 26 of the vibrating mechanisms 21, 22. Sheave 31 is mounted on the end 27 of operating shaft 25 and sheave 32 is mounted on the end 28 of operating shaft 26. The sheaves 31, 32 are axially spaced apart from each other a predetermined distance d^2 . The two distances d^1 and d^2 are both at least sufficient to permit the endless belts 24 to pass therebetween. Thus each of the endless belts 24 can be slipped between the two sheaves 31, 32 and then moved outwardly to be placed in driving connection with the sheaves.

Timing means are provided to connect the two vibrating mechanisms 21, 22 together to establish and maintain a predetermined timing between the vibrations produced by each of the mechanisms. In the preferred embodiment shown in the drawings the timing means comprises a pin 35 fitted in apertures 36, 37 in the sheaves 31, 32. This can more clearly be seen with reference to Fig. 3 which is an enlarged fragmentary portion of Fig. 2 showing sheaves 31, 32 and the manner in which timing pin 35 connects these two sheaves in a driving relation.

The timing pin 35 is of generally cylindrical shape having a head portion 38, a main body portion 39 and a portion 40 of smaller diameter than the main body portion 39. The portions 39 and 40 are connected by what may be a conical section 41. The pin 35 is provided with a threaded end portion 42. A nut 43 is shown mounted theron for drawing up on the pin 35 to seat the conical section 41 in a recess 44 provided around aperture 37.

In order to provide flexibility in the connection between the operating shafts 25 and 26 aperture 36 is bored a larger diameter than the pin portion 39 and a rubber bushing 45 is inserted into the aperture 36. The bushing 45 encompasses the portion 39 of the pin 35 and by being interposed between one of the sheaves 31 and the pin 35 the connection between the two sheaves and the two operating shafts is thereby made flexible.

With the described construction vibratory forces are transmitted smoothly and evenly along the entire length of the transverse support 20 to provide an improved distribution of material on the screening surface 13 as it passes through the box 10. Slight misalignment of the vibrating mechanisms 21 or their internal parts will not, because of the flexibility in the connection between them, appreciably disturb such even distribution of material. And when it becomes necessary to replace the endless belts 24 this is easily accomplished by removing the nut 43 from the threaded end portion 42 of the timing pin 35 and removing the pin 35 from the apertures 36, 37. With the pin removed it is then possible to easily slip

the old endless belts off of the sheaves 31, 32 and withdraw them through the space between the two sheaves. New endless belts can then be slipped between the sheaves and placed in position on the sheaves. When the new endless belts have been placed in position the pin 35 may then be reinserted in the apertures 36, 37 and the nut 43 once again turned on the threaded portion 42 to draw the conical section 41 of the pin into the recess 44 and once again provide the flexible driving connection between the operating shafts 25, 26 to establish and maintain the proper timing relationship between the vibrations produced by each of the mechanisms 21, 22.

From the foregoing it will be apparent to those skilled in the art that the illustrated embodiment of the invention provides a new and improved vibratory screen and accordingly accomplishes the object of the invention. On the other hand it will also be obvious to those skilled in this art that the illustrated embodiment of the invention may be variously adapted, changed and modified or features thereof embodied in other combinations without necessarily departing from the spirit of the invention or sacrificing all of the advantages thereof. Accordingly the disclosure herein is illustrative only and the invention is not necessarily limited thereto.

What is claimed is:

1. A vibrating mechanism for use with vibrating screens and like vibratable apparatus comprising in combination: a support; a pair of vibrators mounted upon said support, each of said vibrators having a rotatable shaft for operating the vibrator, said vibrators being arranged with said rotatable shafts extending toward each other and axially aligned in linear spaced relationship to each other defining therebetween a first predetermined linear distance; a first sheave fixed on the inwardly extending end of one of said shafts; a second sheave fixed on the inwardly extending end of the other of said shafts in fixed axially spaced relationship from said first sheave and defining therebetween a second predetermined linear distance; driving means; endless belt means drivingly connecting said sheaves to said driving means for rotary movement in response thereto, said first and second predetermined distances being at least sufficient to pass said endless belt means therebetween; and withdrawable timing means extending in bridging relationship between and detachably connecting said sheaves together to establish and maintain a preselected phase relationship between the vibrations of said vibrators when actuated in response to their respective sheaves.

2. In a vibrating mechanism for use with vibrating screens and like apparatus, a support; a first vibrator mounted upon said support; a second vibrator mounted upon said support in close centered facing spaced relationship to said first vibrator, each of said vibrators having a shaft member extending outwardly therefrom, said shaft of said first vibrator extending toward and into substantially registered spaced relationship with said shaft member of said second vibrator; first sheave means mounted upon said shaft member of said first vibrator and rotatable therewith; second sheave means mounted upon said shaft member of said second vibrator and rotatable therewith in fixed spaced relationship to said first sheave means; power means; endless belt means operatively associated with said power means and said sheave means for transmitting rotary movement from said power means to the peripheries of said sheave means to rotate said sheave means in response thereto; and timing means extending in bridging relationship between and detachably connecting said sheave means for positionally coordinating said sheave means relative to each other and said vibrators respectively associated therewith to substantially maintain a preselected phase relationship between said vibrators when rotated in response to said power means, said timing means being withdrawable from said sheaves to permit the reeving of said endless belt

means about said sheave means without dismounting either of said vibrators from said support or disturbing said fixed spaced relationship between said sheaves.

3. In a vibrating mechanism for use with vibrating screens and like apparatus, a support; a first vibrator mounted upon said support; a second vibrator mounted upon said support in close centered facing spaced relationship to said first vibrator, each of said vibrators having a shaft member extending outwardly therefrom, said shaft of said first vibrator extending toward and into substantially registered spaced relationship with said shaft member of said second vibrator; first sheave means mounted upon said shaft member of said first vibrator and rotatable therewith; second sheave means mounted upon said shaft member of said second vibrator and rotatable therewith; second sheave means mounted upon said shaft member of said second vibrator and rotatable therewith in fixed spaced relationship to said first sheave means, each of said sheave means having corresponding apertures defined therein at equal radial distances from the central axis thereof; power means; endless belt means operatively associated with said power means and said sheave means for transmitting rotary movement from said power means to the peripheries of said sheave means to rotate said sheave means in response thereto; and timing means detachably insertable through corresponding apertures in said sheave means and extending in bridging relationship therebetween so as to connect said sheave means for positional coordination relative to each other and to said vibrators respectively associated therewith to substantially maintain a preselected phase relationship between said vibrators when rotated in response to said power means, said timing means being withdrawable from said apertures to permit the reeving of said endless belt means about said sheave means without dismounting either of said vibrators from said support or disturbing said fixed spaced relationship between said sheave.

4. In a vibrating mechanism for use with vibrating screens and like apparatus, a support; a first vibrator mounted upon said support; a second vibrator mounted upon said support in close centered facing spaced relationship to said first vibrator, each of said vibrators having a shaft member extending outwardly therefrom, said
